UNITED STATES PATENT OFFICE.

GEORGE T. BIFFLE, OF NASHVILLE, TENNESSEE.

COMPARTMENT MAIL BOX.

Application filed April 20, 1922. Serial No. 555,767.

To all whom it may concern:

Be it known that I, GEORGE T. BIFFLE, a citizen of the United States, residing at Nashville, in the county of Davidson and State of Tennessee, have invented certain new and useful Improvements in Compartment Mail Boxes, of which the following is a full, clear, and exact description.

My invention relates to mail receptacles, and has for its object the provision of such a device with compartments for "city" and "out-of-town" letters and a compartment for packages.

Another object of the invention is the provision of a plurality of bins to receive the two classes of letters, and a door extending across the entire width of the box at the rear thereof to permit the removal of the bins.

Other objects and advantages of the invention will be apparent from the following description when taken in connection with the accompanying drawing, in which:

Figure 1 is a front elevation of the mail box.

Figure 2 is a vertical section through the box, and

Figure 3 is a horizontal section therethrough.

Referring to the drawing more in detail, the numeral 1 designates the mail box which is adapted for use at a street corner, hotel lobby, railway stations or the like. This box is provided with a horizontal partition

2 which divides the same into upper and lower compartments 3 and 4. In the upper compartment 3 are located the bins 5 whose total width equals substantially the width of the box. Conventional letter chutes or doors

6 lead to each of the bins and may carry any indicia desired. As shown in the drawings, the bins 5 completely fill the compartment 3 and have their outer side walls in engagement with the walls of the box. By this construction it is obvious that the liability of letters falling between the bins and the walls of the box is entirely removed.

The lower or package compartment 4 is provided with a chute 7 in its front wall, but is open in the rear, as is also the upper compartment 3. The compartments are closed by means of a horizontally swinging door 8 which is hinged on one side wall of the box and carries a key-operated lock on its free edge which engages the embossed portion 9 on the adjacent wall of the box.

A flanged portion 10 is provided on the upper front wall of the box for the purpose of receiving a card carrying instructions, etc. The box as constructed and arranged also provides convenient spaces which may be utilized for painted instructions, signs and the like.

In operation the letters are dropped into the proper chutes 6 and gravitate to the bins 5, while packages are inserted in the chute 7 and drop to the floor of the compartment 4. In collecting the mail it is only necessary to unlock and open the door 8 which gives access to both compartments and permits removal of the bins 5, which may then be emptied into the collector's bag.

From the foregoing description it will be seen that I have provided a mail box which is extremely neat and compact in appearance and yet presents a ready means for both the deposit and collection of mail, both letters and parcels.

In accordance with the patent statutes, I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. A mail box including a letter compartment, removable bins in said compartment, letter chutes in the front of the box leading to said bins, and a door at the rear of the box extending across the entire width thereof.

2. A mail box including a transverse partition providing an upper and a lower compartment, bins in the upper compartment, mail chutes leading to said bins, a door extending across the rear of the box and permitting the removal of said bins, and a mail chute leading to said lower compartment.

3. A mail box including a transverse partition providing an upper and a lower compartment, bins in the upper compartment, mail chutes leading to said bins and to said lower compartment, and a door on the rear of said box permitting the removal of said bins and also permitting access to the lower compartment.

GEORGE T. BIFFLE.
